GOLF GREEN OR THE LIKE

Tom Hays North, Jonesboro, Ark., assignor of one-third to Thomas E. Page, Jonesboro, Ark., and one-third to Harold E. Page, Atlanta, Ga.

Application January 28, 1936, Serial No. 61,143

6 Claims. (Cl. 47—48)

My invention relates generally to golf greens or similar botanical arrangements, and particularly to artificial greens having self-irrigating features, and an important object of my invention is to provide green construction of this type which can be kept continually fresh and in playing condition.

Another important object of my invention is to provide artificial greens of the character indicated above which involve water reservoir means which can be made to contain a sufficient amount of moisture and water for maintaining the green in condition, either by supplying water directly to the reservoir means or by supplying the reservoir means through seepage from the surrounding earth.

Another important object of my invention is to provide simple and relatively inexpensive arrangements of the character indicated above which are comparatively easily installed, and which require very little care for the proper maintenance thereof.

Other important objects of my invention will be apparent from a reading of the following description in connection with the drawings, wherein for purposes of illustration I have shown a preferred embodiment of my invention.

In the drawings:—

Figure 1 is a top plan view showing the reservoir installed in conforming depressions in the ground and before the covering has been applied thereto.

Figure 2 is a top plan view of the reservoir.

Figure 3 is a transverse vertical sectional view taken through Figure 2 approximately on the line 3—3.

Figure 4 is a transverse vertical sectional view taken through Figure 2 approximately on the line 4—4.

Figure 5 is a transverse vertical sectional view taken through Figure 2 approximately on the line 5—5.

Figure 6 is a horizontal sectional view taken through one corner of the reservoir.

Figure 7 is a transverse vertical sectional view taken through the completed green and showing the covering laid upon the reservoir.

Figure 8 is a fragmentary top plan view of a modified form of the invention which is devoid of slotted sides and bottom.

Figure 9 is a transverse vertical sectional view taken through Figure 8 approximately on the line 9—9 of Figure 8 and looking upwardly in the direction of the arrows.

Figure 10 is a transverse vertical sectional view

taken through Figure 8 approximately on the line 10—10 and looking toward the left in the direction of the arrows.

Referring in detail to the drawings, the numeral 5 refers generally to an excavation which is made in the ground 6 to the shape of the reservoir 7 and of approximately the same depth as the reservoir so that the top of the reservoir comes approximately flush with the top of the ground. The numeral 8 generally designates a mat of bagging or the like which is laid across the top of the reservoir and has its marginal edges lying also on the edges of the excavation 5, the bagging acting as a porous moisture containing and passing element which not only holds the covering from passing into the reservoir, but carries the moisture from the reservoir to the covering so as to maintain the covering in the proper moist condition.

The covering comprises the relatively thin layer of earth 9 which is laid directly upon the bagging mat 8. A thicker layer of wet straw 10 is laid upon the earth layer 9. A second earth layer 11 thicker than the layer 9 is laid upon the straw.

Upon the earthen layer 11 is laid a comparatively thick layer of cotton seed hulls which is generally designated 12 and which immediately supports the turf layer 13 which is composed of turf and earth. Of course, the layer 13 may be devoid of grass if desired, but the arrangement of the invention particularly contemplates the presence of grass in the layer 13. As indicated in the drawings, the various layers which form the cover extend beyond the sides and ends of the reservoir 7 and its excavation or pit 5.

Although the reservoir of the present invention may assume forms other than the generally rectangular form illustrated in Figures 1 and 2, the rectangular form best embodies the invention.

The reservoir, already generally designated 7 comprises the longitudinal side members 14 and 15 and the transverse members 16, 17, 18, 19, 20 and 21.

As indicated in Figure 1, the device of the invention may consist of several units of the type shown in Figure 2, laid edge to edge or in some other suitable arrangement. These units are severally generally designated by the numeral 22.

It will be observed that the longitudinal side member 14 has at one end a reduced extension 23 which has rising therefrom a vertical conduit 24 which is of a sufficient height to penetrate the covering and rise to a position approximately flush with the turf layer 13, so as to be readily

accessible to receive water for filling the interior of the reservoir whenever required. A suitable cover (not shown) may be provided for the upper end of the conduit 24 to keep out dirt and to preserve the continuity of the green surface.

Except for the extension 23 the longitudinal side members 14 and 15 are identical in construction, each consisting of a pair of floor boards 25 and 26 which are laid edge to edge and abutting 10 as indicated by the numeral 27. From the top of the floor boards rises a rectangular frame 28 which acts as a brace for the boards 25 and 26 and also for the vertically spaced side wall forming boards 29 and 30 and 31 and 32. The spacings 33 and 34 between the last-mentioned boards provide for seepage of the moisture and water through the side walls, so that exchange of moisture may take place between the earth surrounding the side member 14, and the interior thereof.

Fastened to the top of the frame 28 and to the upper edges of the side walls are the top forming boards 35, 36, 37, 38 and 39 which have their opposed edges spaced as indicated by the numeral 40 to provide for exchange of water and moisture between the interior of the side member 14 and the covering which lies upon the tops of these boards.

Each of the transverse members already 30 denominated comprises similarly related floor boards 25' and 26' and similar wall forming boards 31' and 32' spaced as indicated by the numeral 34' and top forming boards 35', 36', 37', 38' and 39' similar to the top forming boards of the side members 14 and 15.

The respective ends of the side members communicate with the corresponding ends of the transverse members as clearly shown in Figures 5 and 6.

40 The position of one of the side member supporting frames or braces 28 is clearly shown in Figure 6 while the position of one of the braces or frames 28' of the transverse members is clearly shown also in Figure 6 and in Figure 5. Several of the respective supporting frames or braces are used throughout the lengths of the side and transverse members according to requirements.

Experience has shown that a very adequate material for constructing the units 22 is cypress lumber, of two-by-four inch size, as a unit constructed of this material lasts indefinitely and functions with the greatest satisfaction for the particular purpose.

The embodiment shown in Figures 8, 9 and 10 55 is of the same general form and arrangement as the above described embodiment but has instead of the slotted sides and bottom, the closed sides formed of the planks 29^a, 30^a, 31^a, 32^a and the planks 29^b, 30^b and 31^b, 32^b whose contiguous edges are abutted to form solid walls. The bottoms of the reservoir channels in the present embodiment are formed of the planks 25^a, 26^a which have their contiguous edges abutted to form a solid bottom.

65 The interior brace structures 28^a and 28^b are the same as the interior brace structures of the first described embodiment.

The tops of the reservoir channels are formed of spaced narrower planks 35^a, 36^a, 37^a, 38^a, 70 39^a in the case of the longitudinal channels 14^a, and 35^b, 36^b, 37^b, 38^b, 39^b in the case of the transverse channels 16^a, 17^a, 18^a, 19^a, 20^a, 21^a, so that the water escape slots 21^b are formed through which the water travels into and irrigates the 75 green structure.

It is to be understood that a green structure or the like similar to that shown in Figure 1 is or may be imposed on the last described embodiment and for the same purposes. While in some installations the first described form of the invention is suitable and efficient and supplies a relatively large amount of water, this form uses much more water than the last described form of the invention and for this reason may not be suitable for certain installations where reasons of water economy and the type of soil may dictate a smaller expenditure of water, in which case the last described embodiment or form of the invention would be more suitable. Obviously the closed sides and bottom of the second embodiment obviate the escape of water which takes place through the side slots 33, 34 and 33', 34' and the bottom slots 27 of the first described form and permit the escape of water in quantity only through the slots formed between the narrow slats of the top. Where sufficient water irrigation can be achieved with the smaller expenditure of water due to soil conditions and the like, the last described embodiment is to be recommended.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. In artificial green of the character described for installation in a ground surface, a water and moisture reservoir laid in a conforming depression in the ground surface and having openings in its top, an absorbent fabric sheet lying on the top of the reservoir, and a plurality of green-forming layers laid thereon.

2. In artificial green of the character described for installation in a ground surface, a water and moisture reservoir laid in a conforming depression in the ground surface and having openings in its top, an absorbent fabric sheet lying on the top of the reservoir, and a plurality of green-forming layers laid on said sheet, and a conduit leading from the upper surface of the green into said reservoir for conveying the water into the reservoir.

3. A device of the character described for installation in the ground surface, said device comprising a reservoir to be laid in a conforming depression in the ground surface, and an absorbent covering laid on the ground surface and on the top of said reservoir in moisture-receiving relation to the reservoir, said reservoir consisting of at least one unit comprising a plurality of transverse conduits and a pair of longitudinal conduits in communication with the ends of the transverse conduits, said conduits being formed with longitudinally distributed water escape openings in the sides and top thereof.

4. A device of the character described for installation in the ground surface, said device comprising a reservoir to be laid in a conforming depression in the ground surface, and an absorbent covering laid on the ground surface and on the top of said reservoir in moisture-receiving relation to the reservoir, said reservoir consisting of at least one unit comprising a plurality of transverse conduits and a pair of longitudinal conduits in communication with the ends of the transverse conduits, said conduits being formed with longitudinally distributed water escape openings in the 75

top thereof, the sides of said conduits being solid and devoid of openings.

5. A device of the character described and adapted for installation in a conforming opening in the ground surface whereby the upper part of said device is below ground level, said device being polygonal in plan, said device comprising spaced end members, and a plurality of transverse members, the outer ends of said transverse members being connected to and in communication with the respective end members, each of said members comprising an imperforate bottom, imperforate side walls, and a top containing several slots formed therethrough and extending substantially the length of the respective member.

6. A device of the character described and adapted for installation in a conforming opening in the ground surface whereby the upper part of said device is below ground level, said device being polygonal in plan, said device comprising 5 spaced end members, and a plurality of transverse members, the outer ends of said transverse members being connected to and in communication with the respective end members, each of said members comprising an imperforate bottom, 10 imperforate side walls, and a top containing several slots formed therethrough and extending substantially the length of the respective member.
